UNITED STATES PATENT OFFICE

NORMAN EISENSTADT, OF NEW YORK, N. Y.

DESIGN FOR A CORD EMBROIDERED TEXTILE FABRIC

Application filed March 31, 1933. Serial No. 47,653. Term of patent 7 years.

To all whom it may concern:

Be it known that I, NORMAN EISENSTADT, a citizen of the United States of America, residing at 202 West 40th Street, in the city of New York, county of Manhattan, and State of New York, have invented a new, original, and ornamental Design for Cord Embroidered Textile Fabric, of which the following is a specification, reference being had to the accompanying drawing, forming a part thereof.

The figure is a plan view of a piece of textile fabric showing my design including the selvage edge of the fabric. The design shown

is repeated to the opposite selvage edge of the fabric; that is, the opposite edge of the fabric is the same as that shown.

The characteristic feature of my design resides in the multi-colored corded embroidered fabric.

I claim:

The ornamental design for a cord embroidered textile fabric as shown and described.

In testimony whereof I have signed this specification.

NORMAN EISENSTADT.
